*W. E. Arnold,
Washing Machine.
Patented Jan 11, 1830.*

Jan. 11, 1830

William C. Arnold of Haddam, county of Middlesex
State of Connecticut

Letters Patent

The schedule referred to in these Letters Patent, and making part
of the same, containing a description in the words of the said William
C. Arnold himself of his improvement in a Machine for washing
clothes -

To all, to whom these presents shall come: Be it known,
that I William C. Arnold of the town of Haddam, in the county
of Middlesex and state of Connecticut, have invented a new & useful
improvement in a Machine for washing clothes, & that the following
is a full & exact description of the construction & operation of the said
Machine as invented or improved by me -

This machine consists of a box fourteen inches long, twelve
inches wide & twelve inches deep - At each end of the box & within
it, is a piece of wood or plank five inches wide, one inch and a half
thick on one side and brought down regularly so as to come to an
edge on the other side - These pieces are fastened in the upper part
of the box with the thin edges downwards, by means of nails, or by
soldering the ends of them in places cut for that purpose in the sides
of the box - At an equal distance from each end of the box, near
the top, is a pin one inch in diameter, extending across the box
& entering holes in the sides of the box - This pin passes thro' and
supports two shafts of wood, eighteen inches long, two inches wide
and one inch thick - The holes in the shafts, through which the pin
passes are eight inches from one end of the shafts, and ten inches from
the other - These shafts are six inches distant one from another
and are articulated to move on the pin - On the larger
or lower end of these shafts are four pieces of boards or plank, two
on each side of the shafts fastened with nails - These pieces are so long
as to extend across the width of the box - The pieces at the ends of the
shafts are three inches wide and one inch and a half thick on the side

near the end of the shafts and bent back or reduced to a thin edge
 on the other side. The other two pins are six inches wide, five eighteens
 of an inch thick on one side which adjoins the thin edge of the other pins
 and bent back or brought to a thin edge on the other side. This forms a dial
 or washer & moves on the box. Near the upper end of the shafts is a pin
 half an inch in diameter which connects the shafts. At one end of the box
 on the outside is a post or upright, one inch and a half square, rising
 six inches above the top of the box. This post is in the center of the end
 and fastened to it by screws. On the upper end of the post is a tenon
 an inch in length and half an inch thick. This tenon is inserted in
 a jaw or opening half an inch wide, five inches long in the lower end
 of a stick eighteen inch long and standing upon the post. A pin connects
 the tenon with the jaw. The upper end of the stick on the post is made
 properly for a handle for eight or ten inches. The remaining part of
 it is square & of the same dimensions as the post. The lower end of it is a
 little rounded. From the upper end of the opening or jaw an arm
 or pitman eight inches long, secured in the jaw by a pin, extends to the
 pin, which joins the top of the shafts and is connected with this pin
 by the pins passing thro' a hole in the end of the arm. At the bottom
 of the box, are four elastic pieces of wood a quarter of an inch thick
 and about three inches wide, extending from one end of the box to
 the other at a small distance from each other, resting on the bottom
 of the box in the middle and bent into a regular curve, corre-
 sponding with the circular motion of the bottom of the washer.
 When the machine is in operation, the ends of these pieces press
 against the ends of the box and in that way keep their place. Upon
 the top of the box is a cover in two parts which may be taken off
 at pleasure. Near one corner is an orifice for letting off the water
 when necessary. ~~It is made to~~ ~~the~~ ~~box~~ ~~turn~~ ~~on~~ ~~the~~ ~~box~~
 the box on each side of the washer and the washer is fastened
 by moving the handle of the stick on the top of the post, back-
 ward with the hand. By this means the latter is pressed
 against the ends of the box so the pieces of wood are pressed into

ends and are made clean. The dimensions of the Machine may be varied. It may be made on a large scale & put in motion by water or other suitable power. The bottom of the box may be without the elastic pieces and consist of one solid piece properly curved from one end to the other. The ends of the box may be so placed as to make an acute angle with the bottom on the outside, & thus to dispense with the pieces of plank on the ends. The Machine may be constructed with two or more dashers each of which may be moved by a separate power in the method above described. Two dashers may be moved by a single power by placing two shafts at the end of the box at a suitable distance from each other, passing above the box supporting a pin, passing thro' them and the middle of the jaws or opening, and by adding another arm or pitman to go from the lower end of the jaw to the pin in a second pair of shafts.

The machine may be made double by attaching another similar to the one above described to the end of it so as to be operated upon by the same power. The dasher may be varied in its construction. The boards may be of an even thickness or thicker at one end & placed lengthwise of the shafts with the thicker end down; and fastened to cross pieces joining the shafts. This machine may be put in motion by means of a crank at one end of the box connected with the pitman, or arms, or instead of a pitman, with the hand and roller. In the latter case a roller is placed at each end of the box one of them, turning on a fixed pin & the other fixed on a crank, & turning with it, & the hand is fastened at one end to the fixed roller & at the other to the pin near the top of the shafts of the dasher, & passing round the rollers. A double or triple crank may be used for the purpose of moving two or more dashers.

What I claim as new in the above described Machine & that for which I ask an exclusive privilege is the arrangement and putting together of the various parts which constitute the same in the manner above specified, & the application thereof, of the powers and principles embodied in the operation of said machine in the form and method above set forth and described to the purpose of washing clothes. In witness
